Patented Dec. 16, 1924.

UNITED STATES PATENT OFFICE.

ALBERT G. DOUTHITT, OF KENYON, MINNESOTA.

CAN WASHER.

Application filed July 19, 1923. Serial No. 652,597.

To all whom it may concern:

Be it known that I, ALBERT G. DOUTHITT, a citizen of the United States, residing at Kenyon, in the county of Goodhue and

5 State of Minnesota, have invented certain new and useful Improvements in Can Washers; and I do declare the following to be a full, clear, and exact description of the invention, such as will enable others skilled 10 in the art to which it appertains to make and use the same.

My invention relates to a continuous power-driven washer for open-ended cans, the principal object being to produce a 15 washer that can be installed in the feed line to a can filling machine, in such a manner that it will thoroughly wash the insides of the cans, both water and steam being preferably used in the washing operation.

20 It is a further object of the invention to provide a washer which is simple in construction, easy to install and operate, cheap to manufacture, and thoroughly efficient for the purposes intended.

25 With the foregoing in view, the invention resides in the novel subject matter herein-after described and claimed, the description being supplemented by the accompanying drawings.

30 Figure 1 is a side elevation of a can washing machine constructed in accordance with my invention.

Figure 2 is a vertical sectional view in a plane parallel with the side of the machine 35 shown in Fig. 1.

Figure 3 is a detail sectional view on line 3-3 of Fig. 2.

Figure 4 is a horizontal sectional view on the plane indicated by line 4-4 of Fig. 2.

40 Figure 5 is a side elevation of the can feeding wheel.

In the drawings above briefly described, the numeral 1 designates a substantially cylindrical metal casing having a steam escape hood 2 at its upper side and a water outlet 3 at its bottom. This casing is preferably, although not necessarily, constructed in the manner shown and includes a substantially annular wall 4 having inwardly turned side flanges 5, and a pair of sides 6 secured to said flanges. A plurality of circumferentially spaced track-supporting bars 7 extend between the outer edge portions of the sides 6 and preferably have outwardly bent ends 8 secured by screws or the like 9 to said sides and to the flanges 5. These

bars 7 serve as stiffening means for the casing, as well as supports for a pair of substantially annular tracks 10 for a purpose to appear.

60 A can feeding wheel 11 is mounted within and concentric with the casing 1, upon a shaft 12, and any desired means, such as the gearing 13 and belt wheel 14, may be used for driving said wheel. The rim 15 of the wheel 11, in the present disclosure, is provided on its outer surface with a relatively wide annular metal band 16 having an annular flange 17 at one edge. The band 16 is also provided with a plurality of circumferentially spaced fins or flights 18 which coact with the flange 17 in forming a plurality of transverse can-receiving pockets at the periphery of the wheel, which pockets are open at their outer sides and at one end. 70 An annular track 19 is secured to one of the casing sides 6 at the open ends of these pockets, and this track, together with the tracks 10 above described, retain the cans C 75 in the pockets.

75 For feeding the cans into the pockets of the wheel 11, an inclined chute 20 is shown extending through an opening 21 in the casing wall 4, the upper side of said chute being provided with a curved spring 22 which extends to a point adjacent the pockets and will prevent jamming of any of the cans as they are supplied to the wheel. As the cans travel around in the casing, they are washed by the means hereinafter described, 80 and are then discharged through a suitable outlet chute 23.

85 For washing the cans, I prefer to employ both a water pipe 24 and a steam pipe 25, said pipe 24 having a nozzle 26 at one side of the casing for discharging water into the open ends of the cans C, while the pipe 25 communicates with an arcuate steam spray pipe 27 which will discharge steam into the cans after they have been washed with the water. Surplus steam escapes through the hood 2 and all water drains from the casing 1 through the outlet 3.

90 By providing the novel construction herein disclosed or a substantial equivalent 105 thereof, it will be seen that a machine is provided which will effectively carry out the objects of the invention, and as excellent results may be obtained from the general structure disclosed, it is preferably followed, but 110 within the scope of the invention as claimed, numerous minor changes may be made.

I claim:

1. A washing machine for open-ended cans comprising a rotatable can feeding wheel having transverse peripheral pockets closed at one side of the wheel and open at the other side thereof to expose the open ends of the cans, a cylindrical casing wall around the wheel having a can inlet and an outlet, flat casing sides at the sides of the wheel secured to said wall, track-supporting bars extending between and secured to said sides at the periphery of the wheel, substantially annular track-bars secured to said first named bars to retain the cans in said pockets, and means for forcing a cleaning medium into the cans during their travel from the inlet to the outlet.
2. A washing machine for open-ended cans comprising a rotatable can feeding

wheel, an annular band surrounding the rim of said wheel, said band being equipped with a marginal radially extending flange and being further provided with circumferentially spaced fins forming a plurality of transverse can-receiving pockets, a casing in which said wheel is confined, track-supporting bars secured to the peripheral wall of said casing inside of the latter and extending transversely thereof, substantially annular track-bars secured to said first named bars and forming transversely spaced tracks, and means for conveying a cleaning fluid into the open ends of the cans during their travel in said casing.

In testimony whereof I have hereunto affixed my signature.

ALBERT G. DOUTHITT.
